UNITED STATES PATENT OFFICE.

SAMUEL RAINBIRD, OF NORWICH, COUNTY OF NORFOLK, ENGLAND.

IMPROVEMENT IN GRAPPLING AND RAISING SUNKEN VESSELS, &c.

Specification forming part of Letters Patent No. 35,172, dated May 6, 1862.

To all whom it may concern:

Be it known that I, SAMUEL RAINBIRD, of Norwich, in the county of Norfolk, in that part of the United Kingdom of Great Britain and Ireland called England, builder, have invented new and useful Improvements in Grappling and Raising Sunken Vessels and other Submerged Bodies, and in Apparatus for that Purpose; and I do hereby declare that the following is a full and exact description thereof, reference being had to the accompanying drawings, and to the letters of reference marked thereon.

This invention consists of improvements in grappling sunken vessels and other submerged bodies by means of chains and raising them by means of air-vessels in connection with other apparatus, and also of improvements in such apparatus.

I shall first proceed to describe the drawings and afterward the mode of grappling and raising the sunken vessel or other body.

A B and C D in Figure 1 are two graduated chains by which the sunken vessel or other body is to be raised. Each of these two chains has two rings or similar guides, as shown at E F and G H. These rings can be fixed by shackles at different distances apart. These chains are to grapple the sunken vessel and to form a cradle in which it is to be raised, as hereinafter described.

Fig. 2 is a plan showing the sunken vessel D and two steam-vessels or other vessels, A' A', anchored one at each side of the sunken vessel. Two smaller vessels, B' B', are anchored at the head and stern of the sunken vessel and serve to support the chain, which are shown extended and ready to be lowered to grapple the sunken vessel.

Fig. 3 is a side view of an air-cylinder or cylindrical air-vessel made of wrought iron plates riveted together and strengthened by ribs and braces. In extremely long vessels two or more of these air-cylinders are employed, one or more being placed on each side of the sunken vessel, as hereinafter described. Each air-cylinder is provided with a keel and rudder and a ballast-chamber to facilitate the steering of it to the required position before it is lowered down, as hereinafter described.

Fig. 4 is a plan of a stopper by means of which the chains which are to raise the sunken

vessels are fixed in their proper places. This stopper slides between two rabbeted rails, B B, which are fixed on the top of the air-cylinder. A is the stopper, which is a plate of metal perforated by a round hole and a straight slit communicating together. The round hole is large enough to allow of the free passage of the grappling-chain c, while the slit is only wide enough to take a link of the chain edgewise. This plate is moved backward or forward by a screw, d, which is worked by ropes or chains round a drum, e, connected with the screw, the ropes or chains being reversed to each other round the drum. By pulling the rope or chain a the slit of the plate A is brought into contact with the chain c, which is thus stopped and fixed, while by pulling the rope or chain b it is again released.

Fig. 5 is a longitudinal section of the air-cylinder, showing the internal arrangements. A A is an air-tight floor, the space below which is filled with water to serve as ballast for keeping the cylinder in one constant position. The air-cylinder is divided into two compartments or more by a partition or bulk-head, E, so that either compartment may be filled with air or discharged independently of the other.

A number of cylindrical tubes, 1 2 3 4 5 6, open at both ends, are carried through the air-cylinder and serve for the reception of the grappling-chains. (Shown in Fig. 1.) h h are valves for the entrance and escape of the air from each compartment. They are opened and closed by means of ropes in a similar manner to that in which the stopper (shown in Fig. 4) is worked. These valves communicate with flexible tubes which are carried up above the surface of the water.

A tube, d, passes through the air-cylinder near to each end and contains a valve, e, communicating with the interior of the air-cylinder. This valve is opened and closed by an iron rod the end of which ascends to the top of the air-cylinder and is worked by a lever or winch at the top. When the air-cylinder is rather more than half-filled with water, the valve e, Fig. 5, is closed. This part of the apparatus is shown on a larger scale in Fig. 9, which is a section, and Figs. 10 and 11, which are front and back views, of the same. E is the valve. A B in these figures is a bent pipe or radial tube working in a stuffing-box

at the point B, which is in the axis of the air-cylinder or ponton and furnished with a rotary screw-valve at B. This valve is opened and shut by the chains or ropes f and g, Figs. 5 and 9. These chains are passed in opposite directions round two grooves in the circumference of each valve, so that by pulling one chain the valve is screwed up to its face and closed and by pulling the other chain the valve is unscrewed and opened. This pipe A B serves for the escape of the water when air is forced into the air-cylinder. As this pipe is free to turn in the stuffing-box at the point marked B in Figs. 9 and 10 and d in Fig. 5, its own weight keeps it in a vertical position, so that it is always suitably placed for the discharge of the water, although the air-cylinder may roll over on one side.

Fig. 6 is an end view, and Fig. 8 is a side view, showing the mode of applying the improved apparatus for raising a sunken vessel or other submerged body. Fig. 2 is a plan of the same. D is the sunken vessel. A' A' are two steamers which I employ to tow the air-cylinders or pontons to the spot. A man is sent down in a diving-dress to ascertain the position of the sunken vessel, and a rope with a buoy is attached to each end of it. The two steamers are moored in the position shown in the figures, and two smaller vessels (marked B' B' in Fig. 2) are moored in the positions there shown. One of the chains A B and C D, Fig. 1, is placed on board each steamer, and the rings E and F and G and H are placed at a distance apart somewhat less than the length of the sunken vessel, or about five feet (more or less) from each end of it. The end A of one chain, Fig. 1, is then passed through the ring G, and the end B is then passed through the ring H. The end C of the other chain is passed through the ring E, and the end D is passed through the ring F. The ends of the chains are attached to capstans or windlasses on each steamer. The portions of the chain which extend from one steamer to the other are extended by means of the smaller vessels, B' B', in Fig. 2, and the chains are then lowered down to the bottom, so as to surround and inclose the sunken vessel or other body. All four windlasses or capstans are then worked, by which means the chains are drawn together until they embrace and grapple the sunken vessel, as shown in Fig. 8. The air-cylinders or pontons are now brought alongside of the steamers. A short piece of chain, Fig. 7, is passed through one of the vertical tubes of one compartment of each air-cylinder, and a similar piece is passed through the corresponding tube in the other compartment, the distance between the two tubes being the same as that between the rings E and F or G and H, Fig. 1. The ends of these short chains are hooked on the side of the air-cylinders, as at b b, Fig. 3, until they are required to be used. They are then unhooked and connected to the ends of the grappling-chains, while the other ends of the

short chains are connected to the windlasses or other lifting-power on board the steamers.

The next operation is to prepare for sinking the air-cylinders. Ropes or chains are then connected to the various short ropes or chains a a f f g g, Fig. 5, for the purpose of working the valves, and also to the ropes or chains a b, Fig. 4, for working the stoppers. The air-tubes are also attached. A valve at top and bottom of each ballast-tank A, Fig. 5, is opened, so as to place it in communication with the rest of the air-cylinder. These valves are not shown in the drawings. They are opened by means of rods ascending through the top of the air-cylinder and worked by means of a lever or winch. Two chains or ropes are attached to the side of the air-cylinder, as at a a, Figs. 3 and 6, for the purpose of lowering the air-cylinder. These chains or ropes are attached to capstans or windlasses on the steamers, and are graduated or marked at intervals of a fathom or other measure similar to the grappling-chains, so as to serve as a guide in lowering the air-cylinder in a horizontal position. Everything being thus arranged, the valves h h and e e, Fig. 5, are opened, and the water flows in, driving out the air at the valves h, and the air-cylinder then begins to subside. When the air-cylinder is rather more than half-immersed in the water, the valves e e are closed and the screw-valves at d d are opened. The water continues to enter at d d until the cylinder or ponton sinks. It is lowered down gradually by means of the graduated ropes or chains, as shown in Fig. 8, being guided in its descent by the grappling-chains. When it has reached the bottom, as shown at C in Fig. 6, the ropes of the stoppers (marked a in Fig. 4) are pulled, and the grappling-chains are thus secured to the air-cylinder or ponton. The other air-cylinder or cylinders are lowered and fixed in a similar manner. A diver may now be sent down to ascertain that everything is properly arranged. The valves h h, Fig. 5, are opened by pulling the ropes attached to them, and air is then forced down the flexible tubes into the air-cylinders by means of air-pumps placed on board the steamers and worked by hand or by the engines of the steamers or otherwise. The water is thus gradually displaced from the air-cylinders, which are thus rendered buoyant. If, however, the air were to be forced in until the air-cylinders acquired sufficient buoyancy to raise the sunken vessel, the consequence would be that it would rise to the surface without any control, and might, in fact, rise head or stern first, or even fall out of the grappling-chains altogether.

To avoid such accidents, I proceed in the following manner: I haul up the graduated chains by means of the windlasses or any other power until they are stretched tight, and I hang a weight on one of the levers of each capstan or windlass, so as to keep a certain amount of tension on the graduated chains. Air is then forced into the air-cylinders un

til their buoyancy, together with the weights on the windlasses, is sufficient to raise the vessel. The weights then descend upon the decks of the steamers. The screw-valves at *d d* in Fig. 5 are now closed, and the windlasses are then worked and the sunken vessel is drawn gradually up to the surface. The graduations or marks on the ropes or chains show at once the position of the vessel and enable the workmen to raise it in a horizontal position. At the same time the labor of raising the vessel is not very great, because the greater part of its weight is balanced by the air-cylinders. If the buoyancy should be found too great, it may be reduced by opening the valves at *d d* in Fig. 5, so as to allow a portion of water to enter and displace a portion of the air, which is allowed to escape by a stop-valve at the upper end of each flexible tube. When the sunken vessel has thus been raised to the surface, it may be towed away into shallow water while still supported by the air-cylinders, or it may be previously lightened by pumping out the water and removing the cargo.

It is not necessary that the grappling-chains should be made of the same strength throughout, as the part above the air-cylinders does not require to be so strong as the lower part. The part above the air-cylinders may be detached by the diver and removed after the air-cylinders have been secured in their proper positions and before beginning to raise the vessel. A safety-valve opening outward and lightly loaded with a spring or weight may be attached to the upper part of the air-cylinder, and it may be protected by being enclosed in a tube like the valves at *d* and *e* in Fig. 5.

In raising a sunken vessel in the manner above described the valves at *B* in Figs. 9, 10, and 11, or at *d* in Fig. 5, are closed when a sufficient amount of buoyancy has been obtained, and the same or nearly the same amount of buoyancy will thus be preserved during the raising of the sunken vessel, for the compressed air will expand and escape at the safety-valve as the vessel rises without affecting the quantity of water contained in the air-cylinders. If the valves at *d d* in Fig. 5 were left open, on the contrary, the compressed air would expand as the vessel rose and would displace a portion of water, and thus increase the amount of buoyancy. This increase of buoyancy must be checked by allowing a portion of air to escape, so as always to leave a part of the weight to be raised by the windlasses or other lifting power.

In lieu of hanging a weight on the lever of the windlass, the workmen may be employed to press upon the lever, so as to keep up a tension upon the lifting chains or ropes.

I have described the air-vessels as being of a cylindrical form and constructed of wrought-iron plates, which I prefer; but other forms and materials may be employed provided that they are made sufficiently strong and air-tight.

I have described the operations as applied to the grappling and raising of sunken vessels; but they may be applied in a similar manner to other submerged bodies—as, for instance, for raising large detached masses of rock when of suitable form to be held by the grappling-chains.

Having now described the nature of my invention and the manner in which the same is to be performed, I wish it to be understood that I do not claim, generally, the raising of sunken vessels by means of air-vessels; but

What I claim is—

1. The mode or modes of grappling sunken vessels and other submerged bodies by the peculiar arrangement of chains hereinbefore described.

2. The mode or modes hereinbefore described of raising sunken vessels and other submerged bodies by balancing a portion only of the weight by air-vessels and then raising the sunken vessel or other submerged body by means of windlasses or similar machinery.

3. The apparatus hereinbefore described, consisting of air cylinders or vessels divided into compartments traversed by tubes with stoppers for securing the grappling-chains, and movable escape-pipes or radial tubes for the escape of the water, together with valves capable of being worked by chains or ropes and other appurtenances, as hereinbefore described.

4. The combination of air - vessels and chains or ropes with windlasses or other lifting machinery, in manner hereinbefore described, for the purpose of grappling and raising sunken vessels or other submerged bodies by such combined apparatus, as hereinbefore described.

Done at Manchester this 16th day of May, 1861.
